APPARATUS FOR PRODUCING UNIFORM
CIGAR FILLERS

Franz Heinrich Benno Stelzer and Herbert Rudolf Kasper, Dresden, Germany, assignors to "Universelle" Cigarettenmaschinenfabrik, J. C. Muller & Co., Dresden, Germany

Application September 2, 1938, Serial No. 228,210
In Germany September 7, 1937

5 Claims. (Cl. 131—79)

The present invention relates to a device for producing uniform cigar fillers and more particularly to devices operating upon short loose tobacco for compressing it into cigar fillers.

An object of the invention is to produce uniform fillers.

A further object is to distribute loose tobacco uniformly in a forming channel and then pressing the tobacco into the desired filler shape.

A further object is to provide a machine of simple structure and low cost for producing fillers of more uniform quality than machines previously known.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a longitudinal vertical section taken through the portion of a cigar filler machine to which the invention is applied.

Figure 2 is a similar view showing the parts in another position of the working cycle.

Figure 3 is a view similar to Figures 1 and 2 showing the parts in a third position in the working cycle.

Figure 4 is a top plan view of the portion of the device shown in Figures 1 to 3 with the tobacco feeding chute removed.

Figure 5 is a fragmentary view in elevation of the left end of the device with the parts positioned as in Figure 2, and

Figure 6 is a view similar to Figure 5 taken with the parts in the position of Figure 1.

This invention resides in the filler forming structure. Tobacco is prepared and handled in a well understood manner in the chute 1 which is open at its lower end and is disposed to drop tobacco through the opening 2 in the upper side of the forming channel 3. The forming channel is a mold having the shape desired for the filler and slidably holding the plunger 4 which delivers the compressing force. The plunger 4 is operated through a link 5 which is driven in any suitable manner from time to time.

The aperture 2 of the forming channel 3 is provided with a pivoted gate 6 which swings about a pivot 7 and is controlled by a link 8. Figure 1 shows the gate 6 in fully opened position and Figure 2 shows the gate in closed position. One of the features of the present invention is the positioning of a plate 9 through the aperture 2. This plate 9 is bolted or otherwise

secured at 11 to a bar 10 which is pivotally mounted at 12 to the end of a control arm 13. A lever 14 controlled by the link 15 is drivingly connected to the bar 10. The arm 13 is pivotally mounted on the machine at 50 so that the plate 9 can be swung into and out of the channel 3, the extreme positions being shown by Figures 1 and 2 respectively. A vibratory motion is imparted to the plate 9 through the link 15 and the lever 14. Tobacco delivered from the bottom of the chute 1 when the gate 6 is in upright position drops upon the face of the plate 9 and due to the vibratory movement thereof is distributed uniformly in the channel.

As will be seen from Figure 2 the plate 9 is only withdrawn from the channel far enough to place its lower edge flush with the inner side of the upper wall of the channel and the gate 6 is provided of a size to close with the plate 9 in the aperture 2.

Tobacco delivered into the channel 3 and distributed by the vibratory plate 9 is pressed, as shown in Figure 2, by the travel of the plunger 4 into the forward end of the channel 3. The channel opens into a vertical chute 20 in which a vertically reciprocable plunger 21 slides. The plunger 21 is operated by a swing lever 22 which has a forked end fitting about the pin 24 mounted at 25 upon the plunger 21. The lower end of the chute 20 is normally covered by a plate 28 which is attached to the lever 29 biased by the spring 36. The lever 29 is curved and attached at 51 to a bell crank lever 31 pivotally mounted on the machine at 30. The free arm of the bell crank lever 31 lies in the path of the arm 32 fastened to the lever 22. Figures 1 and 3 show the operation of the plunger 21 and cover 28. The channel 20 is only opened when the plunger 21 is driven downwardly so that no free tobacco is deposited upon the belt 35 of the cigar forming machine. The channel is only uncovered by swinging the plate 28 to its open position, as shown in Figure 3, when a complete filler is formed by the plunger 4 and the other parts of the machine are in positions to receive the filler. Figure 3 shows the cigar rolling parts of the machine positioned to receive the filler. A bight has been formed in the belt 35 by the upward movement of the bar 26 and the roller 52. The normal level of the belt is that of the upper surface of the fixed table 27.

When the plunger 21 is in raised position in the channel 20, the plunger 4 in the filler forming channel 3 compresses tobacco 33 into the forward end of the channel. During the initial

compressing movement of the plunger 4, the tobacco 33 and 34 is compressed against a swinging knife 16 which at this phase of the operation is disposed in its upward position, as shown in Figure 1. After pressure has been exerted on the tobacco for a short time the knife 16 is swung downwardly and the plunger 4 advances the tobacco into the channel 20, the plunger 21 being withdrawn in the meantime. When compression is complete the swinging knife 16 is brought upwards to sever the outer portions of the compressed tobacco which then is free to fall in the channel 20 upon the cover 28. This cut filler rests on the cover 28 until it is pressed out as before described.

Figures 5 and 6 show the knife 16 in greater detail. It will be observed that the knife has a straight cutting edge and is attached to a lever 17 which is pivoted at 18. The outer end of the lever 17 is connected to a controlling link 19 which moves the knife from the position of Figure 5 to that of Figure 6 at appropriate times. The filler forming channel 3 has its lower wall 3' shaped to impart to the pressed tobacco the shape desired for the filler. The knife 16 is brought upwardly against the curved side of the tobacco and the pressure of cutting is then exerted against the plain side or upper side of the compressed tobacco. This permits cutting to take place with a minimum disturbance of the shape of the tobacco. It also permits the use of a knife having a straight edge which is much cheaper and simpler to manufacture than a knife having a complicated curved cutting edge. During the compression stroke of the plunger 4 the knife 16 is maintained in its upper position so that the inner face of the knife forms the closure for the channel 3 against which the tobacco is pressed.

The operation of the device is as follows:

Tobacco dropping into the channel 3 from the shaft 1 strikes the surface of the plate 9 in consequence of which the tobacco is loosened up and at the same time uniformly distributed over the entire width of the channel. After a certain quantity of tobacco has come in this manner the vibration of the plate 9 is stopped by stopping the movement of the link 15. At the same time the arm 13 is shifted from the position of Figure 1 to the position of Figure 2 about its pivot 50 so that the lower edge of the plate 9 lies flush with the inside of the compression channel. Thereafter, by the movement of the control rod 8 the gate 6 is moved to closed position. The plunger 4 is then moved toward the left during which movement it pushes before it the tobacco portion 33 which has just been received into the channel. This tobacco portion 33 is pressed against the mass of tobacco 34 already present in the channel. During the forward movement of the plunger 4 the knife 16 is still in uppermost position as shown in Figure 1. After pressure has been exerted on the tobacco for a short time the knife 16 is swung downwardly and the plunger advances the tobacco into the channel 20, the plunger 21 being withdrawn in the meantime. The knife 16 is now swung upwardly into the position of Figure 3 cutting off the portion of tobacco which projects into the chute 20. The lever 22 is then swung and the plunger 21 is forced downwardly to eject the cut off filler portion. The closure plate 28, actuated by arm 32, uncovers the chute 20 to allow the cut off filler to drop onto the filler rolling machine.

The operations take place in careful sequence and the relation of the operations is best obtained by controlling all of the parts through cams or the like from a single driving source.

5 The manner of connection of the links and levers and the proportioning of the cams is clearly a matter lying within the ability of the skilled mechanician. It is also obvious that driving means other than cams could be employed to accomplish the synchronizing of the various movements described.

10 It is obvious that various changes and modifications may be made in the details of construction and design of the above specifically described embodiment of this invention without departing from the spirit thereof, such changes and modifications being restricted only by the scope of the following claims.

15 What is claimed is:

20 1. In combination with a filler forming device having a forming channel with a tobacco receiving aperture, a compressing plunger in the channel, and a tobacco feeding means for delivering tobacco to said channel through the aperture: a distributor in said aperture beneath said feeding means, vibrating means for the distributor whereby to loosen and spread tobacco passing through said aperture, and a single shifting means for the distributor to move the same into and out of said channel.

25 2. A filler forming device comprising tobacco feeding means, a filler forming channel having an aperture disposed to receive tobacco from said feeding means, pressing means operable in said channel to compress and form tobacco therein, a distributor, and a single movable means for mounting said distributor and for moving said distributor through said aperture and into said channel whereby to loosen and spread tobacco 30 passing through said aperture and for moving said distributor out of said channel so as to permit said pressing means to operate in the channel.

35 3. A filler forming device comprising tobacco feeding means, a filler forming channel having an aperture disposed to receive tobacco from said feeding means, pressing means operable in said channel to compress and form tobacco therein, a distributor, means for vibrating said distributor, and separate means for mounting said distributor for movement into and out of said channel through said aperture.

40 4. A filler forming device comprising tobacco feeding means, a filler forming channel having an aperture disposed to receive tobacco from said feeding means, closure means for said aperture operable to prevent entrance of tobacco into said channel, pressing means in said channel for compressing and forming tobacco therein, and a vibratable distributor mounted for movement into and out of said channel through said aperture, said distributor lying in the aperture beside said closure means when in position to clear said channel.

45 5. A tobacco filler forming device comprising tobacco feeding means, a filler forming channel having an aperture disposed to receive tobacco from said feeding means, pressing means slidably mounted in said channel for pressing tobacco to one end of said channel, a vibratable distributor mounted for movement into and out of said channel through said aperture whereby to loosen and spread tobacco passing through said aperture, said distributor moving out of said channel when said pressing means advances to compress 50 the tobacco, a knife mounted for movement

across the end of said channel to which the tobacco is pressed whereby to cut off portions of pressed tobacco, means for controlling said knife for maintaining the same across the end of said channel while said pressing means is compressing the tobacco, a chute for receiving fillers cut off by said knife and delivering the same, a closure for the delivery end of said chute movable over

and away from said delivery end, a plunger mounted in said chute to eject fillers therefrom, and means for operating said plunger and said closure to open the delivery end of said chute and eject the fillers therefrom.

FRANZ HEINRICH BENNO STELZER.
